UNITED STATES PATENT OFFICE

148,746

DESIGN FOR A PHONOGRAPH NEEDLE

John Walter Berggren, Chicago, Ill.

Application February 25, 1946, Serial No. 126,873

Term of patent 14 years

(Cl. D26—14)

To all whom it may concern:

Be it known that I, John Walter Berggren, a citizen of the United States, residing at Chicago, in the county of Cook and State of Illinois, have invented a new, original, and ornamental Design for a Phonograph Needle, of which the following is a specification, reference being had to the accompanying drawing, forming part thereof.

Figure 1 is a perspective view showing one side of a phonograph needle embodying my new design, the other side, not shown, being substantially the same as the side shown.

Figure 2 is a bottom plan view thereof.

I claim:

The ornamental design for a phonograph needle, substantially as shown and described.

JOHN WALTER BERGGREN.
